UNITED STATES PATENT OFFICE

CELERINO LEANO, OF MANILA, PHILIPPINE ISLANDS

DENOMINATOR MACHINE

Application filed April 2, 1928. Serial No. 266,758.

This invention relates to denominator machines and has for a principal object the provision of a rapid, efficient and greatly simplified means to indicate the smallest number of bills and coins of different denomination comprised in an amount set on the face of the machine.

The invention also resides in certain novel features of construction, combination and arrangement of parts, and improved modes of operation.

Other objects and advantages will be apparent during the course of the following description.

15 In the accompanying drawings forming a part of this application and in which like numerals are employed to designate like parts throughout the same,

Figure 1 is a plan view of the machine, 20 parts being broken away,

Fig. 2 is a vertical sectional view taken on line 2—2 of Fig. 1;

Fig. 3 is a sectional view taken on line 3—3 of Fig. 1;

25 Fig. 4 is a perspective of a pawl supporting member;

Fig. 5 is a plan view of the machine;

Fig. 6 is an enlarged detail sectional view taken on line 6—6 of Fig. 5;

30 Fig. 7 is a plan view of a chart employed in connection with the invention;

Fig. 8 is a detail sectional view taken on line 8—8 of Fig. 1, the view illustrating a pawl and ratchet mechanism employed in 35 connection with the zero setting device;

Fig. 9 is a vertical transverse sectional view taken on line 9—9 of Fig. 12;

Fig. 10 is a vertical transverse sectional view taken on line 10—10 of Fig. 12;

40 Fig. 11 is a vertical transverse sectional view taken on line 11—11 of Fig. 12;

Fig. 12 is a plan view of a set of numbered disks and the means to turn the disks individually in a step by step manner;

45 Fig. 13 is a fragmentary perspective illustrating a portion of the cover plate for the machine and the means to hold the carriages in a manually set position.

In the drawings, wherein for the purpose 50 of illustration is shown a preferred embodiment

of the invention, the numeral 20 designates a casing which may be of any preferred material and outline and which as illustrated in Figs. 2 and 3 carries a number of shafts 21. One end of each shaft 21 is provided with a bevel pinion 22 engaged by a pinion 23 mounted upon a driving shaft 24. Attention is now directed to Fig. 5 which illustrates that the shaft 24 which supports all of the pinions 23 is extended exteriorly of the 55 casing and has connection with a crank 26 by means of which the shaft 24 may be turned. It will be seen with reference to Fig. 1 that the shaft 24 is provided with a ratchet 25 engaged by a pawl 27 to limit the turning of 60 the shaft 24 in one direction.

It is thus seen that all of the shafts 21 are turned simultaneously and at the same speed and it is now pointed out that each shaft is provided with a predetermined number of 65 disk-shaped racks 28. Some of the disk-shaped racks have more teeth 28 than others and this is determined by the chart illustrated in Fig. 7.

The disk-shaped racks 28 engage the teeth 70 of ratchet wheels 30 carried by brackets 31 and slidably mounted upon squared shafts 32. There are ten teeth on each ratchet wheel 30 and the extent to which the particular ratchet wheel is turned is governed by the 75 number of teeth on the rack 28 engaged thereby. For example, if one of the racks 28 is provided with three teeth 28a and is engaged with one of the ratchet wheels 30, that ratchet wheel will be turned three steps to impart a 80 similar movement to its squared shaft 32. At this point it might be stated that a plurality of numbered or indicating disks 61 are 85 in effect mounted on the shaft 32 so that each time the shaft 32 is turned one step the disks 61 will be moved accordingly by a means to be fully hereinafter described.

Before proceeding with the description of the numbered disks 61 and associated elements it is desired to direct attention to Figs. 90 2 and 3 which illustrate that the brackets 31 are secured to the under side of carriages 40 and the carriages are in turn provided at opposite sides with pairs of wheels 41 which operate upon tracks 42 whereby the carriages 100

may be moved forwardly and rearwardly by the operator. Each carriage is provided with a plunger or handle 45 extended up through the cover plate 46 of the machine and having a knob 47 by means of which the carriage 5 may be easily manipulated. The stem of the handle is extended through a bushing or sleeve 49 which, as illustrated in Fig. 13, is provided with oppositely located notches or recesses 50 to receive lugs 51 on the stem. 10 However, the lugs 51 are normally engaged in notches 52 in locking plates 53 so that the carriages are held in set positions. Fig. 2 illustrates that a spring 55 is engaged with the lower end of each plunger or handle 45 to urge the same upwardly whereby the lugs 51 are normally received in the notches 52. 15 However, it is a simple matter to depress the handle 45 to move one of the carriages along the track.

At this point it might be stated that the notches 52 correspond in number and register with the numbers on the face of the cover plate of the machine as clearly shown in Fig. 1. Thus, if it is desired to position a particular carriage at the numeral 5 it is merely necessary to depress the handle 45 of the same and slide the carriage along the supporting track 42 until the stem or shank of the handle is opposite the numeral 5. The handle is now released and the spring 55 will move the handle upwardly so that the lugs 51 are received in the notches 52. This locks the carriage in the desired position. Attention is directed to the fact that the weight of each carriage is borne by the wheels 41 and the track 42 so that the ratchet wheels 30 are relieved of this strain. This permits the ratchet wheels 30 to be freely moved on the shafts 32 by the adjustment of the carriages. This arrangement which is illustrated in Fig. 2 also prevents the carriages from turning up or down on their ends when being moved by the operator.

Attention is invited to Figs. 2 and 6 which illustrate that the outer portions of the shafts 32 are rounded and rotatably support tubular shafts 60, the tubular shafts in turn supporting four number disks generally designated by the numeral 61. Numerals ranging from one to naught inclusive appear on the peripheries of the several disks and may be seen through the sight openings in the extension 63 at the front 55 of the casing. The provision of the four disks makes it possible for a number as high as nine thousand nine hundred and ninety-nine (9,999) to appear in any one of the sight openings. The number disks 60 represent units, tens, hundreds and thousands and, of course, in the operation of the machine the unit number disk is the first to be turned and after this the disk representing tens is turned. Following this the disk representing hundreds is turned and

finally the disk representing thousands is turned. This is made possible by a number of different length pawls 66 which engage ratchet wheels 67 on the sides of the several number disks 61. There are ten teeth 70 in each ratchet wheel 67 and a socket 68. As previously stated, each pawl 66 is of a length different from the adjacent pawl and, more specifically, the pawl which operates the disk representing units is the longest 75 and, therefore, causes the unit disk to turn first. The pawl of the tens disk is shorter than the unit disk and the pawl for operating the disk representing hundreds is still smaller and the pawl for operating the thousands disk is the shortest of all.

The pawls 66 are simultaneously operated and are carried by a pawl plate 70 which is itself pivotally mounted as indicated at 71 for movement about a horizontal axis. Each pawl 66 is engaged by a leaf spring 72 and is urged into engagement with the associated ratchet wheel 67 by the leaf spring. It will be seen that as a result of the rocking or pivotal movement of the pawl-carrying plate 70 the pawls will partake of vertical movement. The vertical movement of the pawls 66 will first cause the number disk representing units to turn in a step by step manner. Fig. 9 illustrates that each 90 ratchet wheel 67 is provided with ten teeth so that the ratchet wheel is turned ten times before the associated pawl is received in the socket 68. When the pawl 66 is received in the pocket or socket 68 further turning 100 of the ratchet wheel 67 and the number disk associated therewith is prevented and the next number disk begins to turn.

The rocking of the pawl plate 70 is brought about by the turning of a ratchet wheel 75 105 on the end of the shaft 32. Attention is directed to Fig. 10 which illustrates that the pawl-carrying plate 70 is provided with a recess or opening 76 to partially receive the wheel 75. The wheel 75 is provided with 110 ten teeth which when turned will present their cam faces or sides to the cross pin 77 and thereby cause the pawl-carrying plate 70 to be moved downwardly against the tension of the spring 78. However, as soon 115 as the cam face of a particular tooth of the wheel 75 moves out of engagement with the pin 77 the plate may return to its elevated position. In other words, the pin 77 may move upwardly into the space between the 120 tooth just passed and the tooth next to be engaged, all of which is clearly illustrated in Fig. 10. The upward movement of the pawl-carrying plate 70 results in the turning 125 of one of the disks one step. On the downward movement of the pawl-carrying plate 70 no turning of the numbered disks results.

Each toothed wheel 75 is mounted on a shaft 32 so that the turning of the shaft 120

32 resulting from the turning of the racks 28 and the wheels 30 engaged thereby will result in the operation of the associated numbered wheels 61. Of course, there is one 5 shaft 32 for each set of four number wheels and there is one pawl carrier 70 for each set of number wheels.

The zero setting mechanism includes a shaft 90 having a butterfly-shaped handle 91 10 which may be manually turned for rotating gears or pinions 92 keyed or otherwise secured to the shaft. Figs. 1, 2 and 6 illustrate that the pinions 92 mesh with pinions 93 having rigid connection with spur gears 94 15 which mesh with spur gears 95 mounted upon the inner end of the tubular shaft 60. When the shaft 90 is manually turned all of the tubular shafts 60 are simultaneously turned so that the springs or pawls 97 carried by the number wheels 61 will engage 20 in notches 98 of the tubular shaft 60 and thereby turn all the number wheels until the same are turned to the zero point.

It will be seen that each numbered disk 25 61 consists of interfitting sections, one of which is provided with the ratchet wheel 67 and the other being provided with the internal pawl or spring 97 for engagement in 30 the notch 98 whereby when the shaft 90 is manually turned all of the disks will be returned to the zero position.

Hand grip 26^a of crank 26 has an axial pin A and a spring B normally urges the pin out so as to engage stop C on end 20 of 25 casing at completion of one revolution so as to prevent crank from being moved too far.

The way my machine operates is as follows:

Suppose we want to find what denominations of currency we need for \$365.83. We 40 slide, by means of knob 47, the first plunger or handle 45 of the first carriage 40 to the left (which represents hundreds of dollars) down to numeral 3 of the slot on the face of the machine. Then we slide the second plunger or handle 45 (which represents tens of dollars) down to numeral 6 of its slot. Then the third plunger or handle 45 (representing units of dollars) we slide down to numeral 5 of its slot. Next we slide the fourth plunger or handle 45 (representing tenths of dollars or tens of cents) down to numeral 8 of its slot. The last plunger or handle 45 (representing units of cents) we slide down 45 to numeral 3 of its slot. Then we turn the crank by means of its handle 26 one full turn and in the sight windows on the face of the machine we will see the number of each denomination of currency we need.

The chart in Figure 7 is for the sole purpose of explaining how the above operation takes place in the machine. The numerals at the extreme left are the numerals placed at the side of each of the five slots 40 on the face 55 of the machine. In order not to interfere

with the other parts of the chart, I have shown these numerals only once and in their position I believed most convenient.

Each long vertical line represents the round shafts 21 and each small vertical line or group of small vertical lines at the left of the long vertical lines represents the toothed racks 28 having as many teeth as there are number of small vertical lines. For example, the last shaft 21 at the extreme right has 75 eight racks.

The first rack has 4 teeth (counting from bottom up)

The 2nd rack has 3 teeth
The 3rd rack has 2 teeth
The 4th rack has 1 tooth
The 5th rack has 4 teeth
The 6th rack has 3 teeth
The 7th rack has 2 teeth
The 8th rack has 1 tooth.

80

So it is with all the rest of the shafts. Where there are no vertical lines 28^a, there are no toothed racks. It must be remembered that these racks are placed and in numbers shown on the chart.

90

The horizontal lines just above the long vertical lines represent the five carriages 40 there are in the machine. The number of long vertical lines included under the entire length of each horizontal line shows on how many shafts each carriage works on and the number of ratchet wheels 30 each carriage carries (there being one ratchet wheel for each shaft) to engage to the toothed racks 28 of the square shafts 32. The first carriage (representing hundreds of dollars) to the left, works only on one round shaft 21 (marked 100) and carries, therefore, only one ratchet wheel 30. If we bring down the first horizontal line or carriage 40 to numeral 3 we will find that the toothed rack which will engage to its ratchet wheel has 3 teeth. This means that said toothed rack will impart 3 steps to the ratchet wheel and, consequently, 3 steps, also, to the numbered disks 61 at the extremity of the shaft. Therefore, in the sight window marked "\$100" we will see the number "3" meaning we need 3 hundred dollar bills.

105

If we bring down the second horizontal line or carriage to numeral 6 we will find that the toothed rack of the first shaft the carriage works on (marked 50) has only 1 tooth, and working similarly as above, we will see the number "1" appear in the sight window on the face of the machine marked "\$50", meaning we need besides 1 fifty dollar bill. The next shaft (marked 20) has no toothed rack in front of the numeral 6 and, therefore, will impart no movement to the ratchet wheel of the carriage. This means that there will appear no number in the sight window on the face of the machine marked \$20 and, hence, we need no twenty dollar bills. The third shaft under the carriage (marked 10) has one rack with 1 tooth in front of numeral 6 and

110

115

120

125

130

working similarly as above, we will find that in the sight window marked \$10 on the face of the machine the number "1" will appear, means we need 1 ten dollar bill. If we bring 5 down the next horizontal line or carriage to numeral 5, and by finding out as in the case of the preceding horizontal line, how many teeth the toothed racks on the shafts the carriage works on, has, we will find that in the 10 sight window marked "\$5.00" the number "1" will appear, no numbers will appear in the sight windows marked \$2 and \$1. The same way with the other two horizontal lines. We bring the fourth horizontal line to numeral 8 15 and the last horizontal line to numeral 3. In the sight windows on the face of the machine we will see that the number 1 in the window marked \$0.50, number 1 in the window marked \$0.20 and number 1 in the window 20 marked \$0.10. In the window marked \$0.05 no number will appear and in the window marked \$0.01 the number 3 will appear.

Having thus described the invention, what is claimed is:

25 1. A denominator machine comprising a base, a plurality of sets of simultaneously rotatable denominizing pinions supported thereon, a set of registering wheels associated with each set of pinions, and a slidably 30 supported carriage on said base having a rotatable pinion cooperating with each set of said first pinions to selectively actuate the corresponding registering wheels.

35 2. A denominator machine comprising a base, a shaft journaled therein, a plurality of denominating pinions secured to said shaft, a slidably supported carriage on said base having a rotatable pinion selectively brought into cooperating engagement with a denominating pinion, a set of registering wheels, and means operatively connecting said registering wheels and said pinions.

40 3. A denominator machine comprising a base, a pair of spaced apart shafts rotatably supported therein, a plurality of denominating pinions secured to one of the shafts and a pinion feathered on the other shaft and means for selectively engaging said second pinion with said first pinions, a register, and means 45 operatively connecting the register with said second pinion.

45 4. A denominator machine comprising a base, a shaft rotatably mounted therein and having a plurality of spaced apart denominating pinions secured thereto, a second shaft arranged in spaced apart parallel relation to said first shaft and having a register rotatably mounted thereon, a pinion feathered 50 on said shaft and a carriage slidably supported on the base and engaging said pinion to selectively bring said pinion into engagement with said denominating pinions, and means operatively connecting the denominating pinions with the register.

55 5. A denominator machine comprising a

base, a shaft mounted therein and having spaced denominating pinions secured thereto, a second shaft mounted in the base and arranged in parallel spaced relation to said first shaft, a register, a pinion feathered on said second shaft, a carriage movably supported on the base and provided with a depending bracket to slidably move said second pinion along said second shaft, means on the carriage for selectively engaging said first and second pinions, and means operatively connecting the register with said second shaft.

60 6. A denominator machine comprising a base, a plurality of spaced apart parallel shafts rotatably mounted therein, interconnected gearing for simultaneously rotating said shafts, each of said shafts having spaced apart denominating pinions secured thereto, a second set of shafts arranged above said first shafts, a pinion feathered on each of said second shafts, a carriage slidably supported on the base, a plurality of depending brackets on the carriage to engage said pinions and to simultaneously bring said pinions selectively into engagement with said denominating pinions, a plurality of registers, and means operatively connecting each register with each shaft of said second set of shafts.

65 In testimony whereof I affix my signature. CELERINO LEANO. 95
